UNITED STATES PATENT OFFICE

167,357

COMBINED AUTOMOBILE LAMP LENS HOUSING AND GRILLE BAR

Henry J. Keane, Grosse Pointe, Mich., assignor
to Chrysler Corporation, Highland Park, Mich.,
a corporation of Delaware

Application September 7, 1951, Serial No. 16,563

Term of patent 7 years

(Cl. D14—18)

To all whom it may concern:

Be it known that I, Henry J. Keane, a citizen of the United States, residing in the city of Grosse Pointe, Wayne County, and State of Michigan, have invented a new, original, and ornamental Design for a Combined Automobile Lamp Lens Housing and Grille Bar, of which the following is a specification, reference being had to the accompanying drawing, forming part thereof, in which:

Fig. 1 is a front elevational view of a combined automobile lamp lens housing and grille bar showing my new design;

Fig. 2 is a top plan view thereof;

Fig. 3 is an end elevational view;

Figs. 4, 5 and 6 are sectional views taken on the lines 4—4, 5—5 and 6—6 respectively.

Fig. 7 is a sectional view taken on the line 7—7 of Fig. 2; and

Fig. 8 is a front elevational view of the combined automobile lamp lens housing and grille bar of my design, the broken line showing therein of a portion of an automobile being for illustrative purposes only.

The characteristic features of my design reside in the portions shown by means of solid lines in the drawings.

I claim:

The ornamental design for a combined automobile lamp lens housing and grille bar, substantially as shown and described.

HENRY J. KEANE.
